UNITED STATES PATENT OFFICE.

JAMES MACFARLANE, OF MALDEN, ASSIGNOR, BY MESNE ASSIGNMENTS, TO HIMSELF, AND CLARENCE FREDERICK JEWETT, OF BROOKLINE, MASS.

LET-OFF MECHANISM FOR LOOMS.

SPECIFICATION forming part of Letters Patent No. 308,681, dated December 2, 1884.

Application filed October 17, 1883. (No model.)

To all whom it may concern:

Be it known that I, JAMES MACFARLANE, of Malden, in the county of Middlesex, of the Commonwealth of Massachusetts, have invented a new and useful Improvement in Let-Off Mechanisms for Looms; and I do hereby declare the same to be described in the following specification and represented in the accompanying drawings, of which—

10 Figure 1 is an elevation, partly in section, and Fig. 2 an end view, also partly in section, showing a warp-beam and the improved let-off mechanism. Fig. 3 is a longitudinal section of one of the extensible bearing-rollers upon which the warp-beam is supported.

The nature of my invention is defined in the claims hereinafter presented.

In Fig. 2 the "let-off" mechanism is shown as adapted to a vertically-movable loom-lay, (a lay of such description being shown in the drawings of the United States Patent No. 278,715;) but it is equally applicable to a horizontally moving or vibratory lay of a common loom, the lay shown at A being provided with 25 a suitable pawl, *a*, to be reciprocated by it in a manner to cause such pawl to engage with the teeth of the ratchet-wheel *B* of the let-off mechanism, and intermittently revolve the said wheel to the necessary extent. Resting 30 on the serrated periphery of the ratchet-wheel is one or more retaining-pawl, *b*, pivoted to the standard *c*, extending upward from the loom-frame *C*. The warp-beam, loaded with 35 yarn, as shown at D, is provided at its opposite ends with journals *d* *d*, each of which is shown as extending between the two prongs *e* *e* of one of two adjustable guide-forks, *E* *E*. These guide-forks rest on two slotted brackets, *F* *F*, and are adjustable thereon nearer to or 40 farther from each other rectilinearly in order to adapt them to warp-beams of different lengths, as may be required. From each fork *E* a screw, *f*, extends down through the slot *g* in the bracket, such screw having a nut, *h*, 45 screwed upon it and against the under side of the bracket. The yarn-load of the warp-beam rests circumferentially upon two supporting and extensible rollers, *G* *G*, arranged horizontally and parallel with each other and 50 at a suitable distance apart. Each of these rollers consists of a long cylinder, *i*, two shorter

cylinders, *k* *k*, and two thimbles, *l* *l*, arranged as shown in Figs. 1 and 3, and adapted to two shafts or spindles, *m* *m*, arranged with their axes in one straight line. The median or 55 longest cylinder *i* has the two spindles or shafts extending into it axially and concentrically, as represented, it being connected to such shafts or spindles by a spline or feather connection, to enable each of them to slide 60 lengthwise in it, (the said cylinder.) Each of the auxiliary or lesser cylinders *k* *k* is applied in the same manner to one of the spindles, there being on one of the spindles, and between the median and one of the lesser cylinders, a spur-gear, *m'*, which is also applied to the spindle by a "feather-connection." Each thimble *l* has a diameter equal to that of the cylinder *i*, and encompasses and fits to one of the cylinders *k*, and consists of a tube, *n*, and 70 a wheel or head, *o*, the latter being inserted in such tube at one end thereof and fastened to it. A set-screw, *p*, screwed through the hub of the wheel *o* and against the spindle, serves to confine such wheel to the spindle. 75

From the above it will be seen that each thimble can be moved lengthwise upon its sustaining-roller, so as to increase the length of the roller *G* as a warp-beam to rest on it may require, the spindle of the thimble being movable at the same time in the cylinder *i* and one of the cylinders *k*. The two spindles rest in bearings in two stationary standards, *r* *r*, extending up between the median and secondary cylinders of each roller *G*, whose gear, *m'*, 85 engages with the terminal gear *n'* of a train, *n'* *o'*, and *p'*, in connection with and driven by the ratchet-wheel *B*.

From the above it will be seen that the extensible bearing-rolls *G* *G* will be revolved 90 intermittently at a uniform speed as the lay may be in movement, and consequently, as the load of the warp-beam rests directly on the said two rollers, such load will be revolved so as to cause its warp-yarns to be delivered or let off at a uniform rate, as may be required.

The loom is to be supposed to be calculated for weaving cloth of any width between certain adopted extremes—as from a yard and a 100 half to two yards, for example. By having each roller *G* extensible, as set forth, it can

be adapted to any warp-beam that can be used in the loom, whatever may be the length of the load of yarn of such beam.

What I claim is as follows, viz:

5 1. The combination of extensible rollers, substantially as described, with mechanism for intermittently revolving them, as set forth, and a warp-beam, as explained.

10 2. The combination of two guide-forks, E, adjustable as described, with a warp-beam, and with two extensible rollers, G, substan-

tially as represented, arranged and provided with mechanism for intermittently revolving them, as and for the purpose specified.

15 3. The extensible roller G, composed of the three cylinders, the two spindles, and the two thimbles, constructed, arranged, and adapted substantially as set forth.

JAMES MACFARLANE.
